United States Patent Office

Des. 188,439
Patented July 19, 1960

188,439

BOX OR SIMILAR ARTICLE

Martin Schnur, 1480 Pleasant Valley Way, West Orange,
N.J., and Mel Appel, 198 Oakwood Drive, Murray
Hill, N.J.

Filed Jan. 12, 1960, Ser. No. 59,016

Term of patent 14 years

(Cl. D58—12)

Fig. 1

Fig. 2

Fig. 3

Fig. 4

Fig. 5

Fig. 6

Figure 1 is an end elevation of a box or similar article, showing our new design;

Figure 5 is a side elevational view of the lid removed from the body of the box; and

We claim:

The ornamental design for a box or similar article, as shown.
